UNITED STATES PATENT OFFICE.

WALTER H. PUMPHREY, OF NEW YORK, N. Y.

COIN-CONTROLLED MECHANISM.

SPECIFICATION forming part of Letters Patent No. 672,807, dated April 23, 1901.

Application filed August 20, 1900. Serial No. 27,513. (No model.)

To all whom it may concern:

Be it known that I, WALTER H. PUMPHREY, a citizen of the United States of America, and a resident of the city of New York, county of New York, and State of New York, have invented certain new and useful Improvements in Coin-Controlled Mechanism, of which the following is a specification:

My invention relates to coin-operated mechanism of a class particularly adapted for use in connection with "slot-machines." In machines of this character the use of a coin for tripping a lock by its weight or the momentum acquired in its passage through a chute ordinarily necessitates the employment of a locking mechanism the coöperating parts of which must be extremely light, delicate, and sensitive to insure a proper response under the action of the inserted coin, and as the machines are usually placed out of doors, exposed to all changes in atmosphere and temperature, a disarrangement or breakdown of such locking mechanism frequently occurs, causing the machines to be labeled "out of order" for a considerable length of time, which thereby increases the cost of maintenance and materially reduces the net earnings.

It is the object of the present invention to obviate the difficulties above mentioned by effecting the release of the machine by means of a hand-lever acting through the medium of a coin. The use of such a lever for this purpose provides the requisite power for operating a tripping device of simpler and heavier construction than is ordinarily employed, and thereby renders the same more efficient and capable of withstanding the wear and tear with little or no liability of disarrangement under ordinary conditions, and, furthermore, insures an immediate response and complete operation upon the insertion of a proper coin.

Mechanism embodying my invention is illustrated in the accompanying sheet of drawings, throughout the several views of which like reference characters indicate corresponding parts.

Referring to the drawings, Figure 1 is a view in diagram of a hand-operated coin-tripping device, the same being illustrated in operative relation to the coöperating parts of a slot-machine; and Fig. 2 is a detail plan view of the coin-carrier, coin-ejector, and coin-finder.

illustrating such parts in their normal position.

In the drawings, I may represent any part 55 of a coin-controlled machine, and in the present instance serves to illustrate the member to be actuated. It may be one end of a bell-crank lever turning about a pivot 2, whose opposite end engages a locking device of, for example, the indicating mechanism of a weighing-machine. Again, the part 1 may represent the lower end of a shutter movable back and forth beneath a sight-opening, such as would be employed in a picture-exhibiting or similar machine. The particular function, however, of the part 1 is unimportant, so far as the present invention is concerned, inasmuch as it is not essential to the operation of the same and is merely employed for the purpose of completing an operative illustration.

6 represents the coin-chute, which ordinarily leads from a slot in the outer casing of the machine and serves to properly direct the coin and deposit it as may be required.

7 represents a two-part trip-lever, which is pivoted at 8 and is provided at its outer end with a pin or other engaging projection 9, adapted, as will be later on explained, to operate with the member to be actuated. It is swinging about the pivot 8 the free end of this lever travels through an arc indicated by the dotted lines 10 10, and thereby clears the member 1. The lever is sustained in proper relation to the coöperating parts of the device by means of a spring 11 and is provided with a cam-face 12 along its upper edge. The parts or members 7^a 7^b of the lever are pivotally united by a pin 13, on which is mounted a roller 14 to serve as a coin-finder. Above 90 the pivot 13 a pin-and-slot connection 15 is provided, which, in connection with the spring 16, serves to maintain proper relation between the parts of the trip-lever.

17 represents a stationary coin-carrier, 95 which is bifurcated at its upper end to provide oppositely-disposed parallel guides 18 18 for the reception of a coin. The entrance to these guides adjoining the lower end of the coin-chute is flared to facilitate the entrance 100 therein of the coin.

19 represents a coin-deflector, which consists of a weighted lever pivoted at or near the lower end of the coin-chute, having one

of its ends projecting within the mouth of the guides of the coin-carrier, as illustrated in Fig. 1. This deflector is so relatively arranged as to yield when engaged by an inserted coin and after the latter has entered the carrier to resume its normal position, in which it provides an inclined face 19^a to deflect or turn the coin downward when the same is ejected from the carrier, and thereby prevents its being forced into the discharge end of the chute.

20 represents a hand-lever loosely mounted upon the shaft 21 and held at one extremity of its movement against its stop 22 by means 15 of a retractile spring 23. This lever carries a roller 24, adapted to coöperate with the cam-face 12 of the trip-lever.

25 represents a coin-ejector, the same being in the form of a dog pivoted upon the 20 hand-lever at 26 and provided with a spring 27, which tends to force the dog upward. This upward movement, however, is limited by means of a stop-pin 28 upon the hand-lever, which latter serves when the parts are 25 in the normal position indicated in Fig. 1 to maintain the ejector clear of the coin carrier and guides, thereby leaving the guides clear and unobstructed for the entrance of a coin.

The operation of the device is as follows:

- 30 Assuming the parts to be in their normal position, as shown in Fig. 1, when it is desired to actuate the member 1 a coin is first inserted and directed by the chute into the coin-carrier, where it lodges. As the coin passes 35 from the discharge end of the chute it engages and forces the pivoted deflector downward out of its path and continues its forward movement the carrier, after which the deflector is again swung upward by gravity. By providing the end of the deflector within the carrier with a knife-edge it may be made to serve in cutting a string, should it be attempted to withdraw a coin dropped into the machine 40 with a string attached to it. The hand-lever is then grasped and moved toward the right or away from its stop, and in being swung about its pivotal center causes the roller to ride over the cam-face of the trip-lever, forcing the latter downward. Owing to the 45 resistance of the spring connection between the members of the trip-lever they move together until the roller at their pivotal center engages the coin in the carrier, and thereafter, under the continued action of the roller of the hand-lever acting on the cam-face of the member 50 7^b, this member is caused to swing downwardly about its pivotal center 13, while the movement of the member 7^a is checked by the coin. As the outer portion of the member 55 7^b only of the trip-lever is now free to move under the action of the cam-roller the arc of travel of the pin 9 is changed, and the pin describes the arc indicated by the lines 10^a 10^b, whereby it is brought into engagement 60 and operates the member 1. As the hand-lever is first moved toward the right the stop-pin 28 is carried away from the ejector, leaving

the outer end thereof free; but the upward tendency imparted to it by its spring is checked by the coin in the carrier, and as the 70 movement of the lever continues the free end of the ejector rides along the under face of the coin until the shouldered portion thereof passes beyond the coin, and thereupon the spring acts to force the ejector upward to the 75 extent of the depth of such shoulder or into such relation with the coin that when the movement of the hand-lever is reversed the shoulder engaging the edge of the coin will force the latter out of the carrier, its discharge being facilitated by the inclined lower face of the deflector, and as the hand-lever resumes its normal position a stop-pin 28 again engages the deflector and depresses the same until the outer free end thereof is clear 85 of the carrier-guides. The return of the parts to their normal position is effected through the action of the several springs described.

Should it be attempted to operate the coin-tripping device without first inserting a coin, the movement of the hand-lever toward the right would merely result in causing the members 7^a 7^b of the trip-lever to move downward in the arc 10^a 10^b. The roller 14 carried thereby 95 would in such an event move downward between the guides without meeting with any interference or obstruction which would tend to change the arc of travel of the trip-lever to the arc 10^a 10^b. The roller 14 in engaging the free end of the ejector-dog would readily 100 depress the same, owing to the greater strength of the spring 16, connecting the members of the trip-lever, as compared to the light plate-spring 27 of the ejector.

105 The advantages of my invention consist in its simplicity of construction, there being comparatively few parts and so relatively assembled as to render all parts of the device readily accessible. Furthermore, from the 110 fact that the parts are few in number and of simple construction they may be given the requisite strength to insure long life and prevent disarrangement and consequent breakdowns of the machine.

115 I do not wish to be understood as limiting myself to the exact construction, &c., herein shown and described, as various parts may be dispensed with and other changes made within the meaning of the present invention. The hand-lever, for example, may be replaced by any suitable device—such as a crank, push-rod, or the like—capable of being operated from the outside of the machine. The form of trip-lever may also be modified, 120 it not being essential that the pivotal connection between the members thereof should be of the form described, so long as a relation exists between the same which enables one part to be adjusted into operative relation 125 with the member to be actuated through the medium of a coin. The deflector may be entirely dispensed with, if desired, by separating the discharge end of the chute and the

entrance to the guides of the coin-carrier to prevent the possible return of the coin into the chute under the action of the ejector. I may also employ other forms of ejector; but as these and other changes would be perfectly obvious to the ordinary mechanic I do not deem it necessary to further describe or illustrate the same, as I consider all such modifications mere changes in form and still 10 within the scope of my invention.

I claim—

1. In coin-operated mechanism, the combination with a member to be actuated, of a suitably-mounted trip-lever normally free to oscillate without engaging said member, means for placing a coin in the path of travel of the lever to serve as a temporary fulcrum therefor, whereby the coin may vary the movement thereof, and a device for oscillating the lever.

2. In coin-operated mechanism, the combination with a member to be actuated of a two-part trip-lever, said parts being movable together and individually, means for placing a coin in the path of travel of the two-part lever, whereby the coin may vary the movement thereof, and operating means for the lever.

3. In coin-operated mechanism, the combination with a member to be actuated of a two-part spring-connected lever adapted to be normally advanced and automatically retracted, the parts of said lever being movable together and individually, means for placing a coin in the path of travel of the two-part lever whereby the coin may vary the movement thereof, and operating means for the lever.

4. In coin-operated mechanism, the combination with a member to be actuated of a two-part trip-lever, said parts being pivotally connected, spring-sustained and movable together or individually, means for placing a coin in the path of travel of the two-part lever whereby the coin may vary the movement thereof, and operating means for the lever.

5. In coin-operated mechanism, the combination with a member to be actuated of a two-part spring-sustained lever, said parts being pivotally connected and movable together or individually, means for placing a coin in the path of travel of the two-part lever, whereby the coin may vary the movement of one of the parts of said lever, and operating means for the lever.

6. In coin-operated mechanism, the combination with a member to be actuated of a two-part spring-sustained lever, said parts being pivotally connected and movable together or individually, means for placing a coin to serve as a stop by engaging said lever parts in the line of their pivotal connection, thereby varying the movement of the lever, and operating means for the lever.

65 7. In coin-operated mechanism, the combination with a member to be actuated, of a two-

part spring-sustained trip-lever, said parts being pivotally connected and movable together or individually, means for placing a coin to serve as a stop in engaging and checking the movement of one of said lever parts and thereby varying the movement of the lever, and a device for oscillating the lever.

70 8. In coin-operated mechanism, the combination with a member to be actuated, of a trip-lever therefor, a fixed coin-carrier and a coin-finder operatively connecting the carrier and trip-lever, together with operating means for the trip-lever.

75 9. In coin-operated mechanism, the combination with a member to be actuated, of a trip-lever therefor, a fixed coin-carrier and a co-operating coin-finder operatively connecting the carrier and trip-lever, said lever and finder being movable about the same center, together with operating means for the lever.

80 10. In coin-operated mechanism, the combination with a member to be actuated, of a trip-lever therefor, a fixed coin-carrier, a coin-finder operatively connecting the lever and carrier and a coin-ejector co-operating with the carrier, together with means for operating the lever.

85 11. In coin-operated mechanism the combination with a member to be actuated, of a trip-lever therefor, a fixed coin-carrier, a chute for depositing a coin in the carrier, a hand-lever for operating the trip-lever and a coin-ejector carried by the hand-lever and adapted to co-operate with the coin-carrier.

90 100 12. In coin-operated mechanism, the combination with a member to be actuated, of a trip-lever therefor, a fixed coin-carrier in operative relation to the trip-lever, a chute for depositing a coin in the carrier, an automatic coin-ejector and a coin-deflector co-operating with the ejector together with operating means for the trip-lever.

95 105 13. In coin-operated mechanism the combination with a member to be actuated, of a trip-lever therefor, a fixed coin-carrier provided with a coin-deflector, a chute in operative relation to the carrier, and an automatic coin-ejector, together with a hand-lever for operating the trip-lever and upon which said 110 115 ejector is mounted.

14. In coin-operated mechanism, the combination of an operating hand-lever, a coin-carrier and suitable means co-operating on the retraction of said lever for automatically ejecting the coin from the carrier.

110 115 15. In coin-operated mechanism, the combination of an operating hand-lever, a coin-carrier and a coin-ejector carried by the lever and co-operating with said carrier on the return of the lever to its normal position.

Signed at New York, N. Y., this 16th day of August, 1900.
